WALL SAFE

Alfred Gordon Le Page, Vancouver,
British Columbia, Canada

Application October 31, 1945, Serial No. 625,799

4 Claims. (Cl. 109—59)

1

My invention relates to improvements in wall safes.

The objects of the invention are to provide a relatively inexpensive safe to be embedded in a concrete or brick wall, which safe is of ample strength and is provided with a locking mechanism disposed at a point remote from the front of the safe, so as to make it extremely difficult for an unauthorized person to tamper with the locking mechanism or open the safe. A further object is to provide a locking bolt which engages the inner end of the safe drawer to lock it in position, as differentiating from the conventional type of drawer where the front of the drawer is locked to the safe casing.

Referring to the drawings:

Fig. 1 is a longitudinal sectional view of the invention showing a circular open ended drawer, taken on the line 1—1 of Figure 2.

Fig. 2 is a transverse section taken on the line 2—2 of Figure 1.

Fig. 3 is a longitudinal sectional view of the locking mechanism.

Fig. 4 is a transverse sectional view taken on the line 4—4 of Figure 3.

Fig. 5 is a longitudinal view of a typical key.

Fig. 6 is a longitudinal view taken on the line 6—6 of Figure 7, showing an open ended rectangular drawer.

Fig. 7 is a transverse sectional view taken on the line 7—7 of Figure 6.

In the drawings like characters of reference indicate corresponding parts in each figure.

The numeral 1 indicates generally a cylindrical casing open ended at the front and provided with a rear end closure 2 which projects beyond the wall 3 of the casing to form a key in the wall into which the safe is to be built. The end closure 2 is provided with a central recess 5 having overhanging peripheral lugs 6 with intervening spaces 7 of similar circumferential width to that of the lugs.

Extending radially of the recess 5 is a pair of grooves 9 in which the legs 10 of an arcuate dog 11 are slidably mounted, the dog 11 is of a width to enter and fill one of the spaces 7 between the lugs 6. The inner edge of one of the legs 10 is cut to form a toothed rack 12, the purpose of which will hereinafter appear.

A cylindrical drawer 14 having a heat insulated wall 15 and a drawer front 16 is slidably insertable within the casing. The drawer 14 is provided with a pull 17 at its outer end and is fitted at its inner end with a flange 18 having arcuate lugs 19 upon its outer periphery which

2

are adapted to pass through the spaces 7 and which when the drawer is turned about its longitudinal axis, lie behind corresponding lugs 6 in the end closure 2. A cover plate 21 is adapted to enclose the grooves 9 of the rear end closure 2 and is fitted with a lock mechanism 22. The lock mechanism 22 consists of a cylinder 24 having an annular end closure 25 and is adapted to be secured to an outer end plate 26, which in the case of the device thus far described, is identical with the cover plate 21. Journalled in the end closure 25 and the outer end plate 26 is a shaft 27 having a longitudinal groove 28 and is fitted at its outer end with a pinion 29. The shaft 27 is fitted with three sliding discs 31, 32 and 33 all of which are urged away from the rear end of the cylinder and from each other by interspaced springs 34. Each of the discs 31, 32 and 33 is provided with an inner peripheral tit 36 which rides in the groove 28 and an outer peripheral gap 37, the tits 36 vary in length, the tit of 31 being short, the tit of 32 being longer and the tit of 33 being still longer. Secured in position longitudinally of the cylinder 24 is a ward strip 39 which is provided with three slots 40 of such depth as to permit the discs 31, 32 and 33 to rotate when they are moved into register with said slots.

A tube 42 extends from the end closure 25 to the front of the casing 1 or the surface of the wall in which the device is fitted. This tube is of the same diameter as the slotted shaft 27 and is adapted to serve as a guide for a key 43. The key 43 is fitted with a knurled knob 44 at its outer end and an operating tongue 45 at its inner end. The tongue is provided with 3 steps 47 which coincide as to spacing with the slots 40 of the ward strip 39, so that when the key is inserted into the tube 42 to its limit, the steps 47 engage the several tits 36 of the discs 31, 32 and 33 progressively compressing the springs 34 until all of said discs are in register with the slots 40, when the key can be rotated, simultaneously rotating the pinion 29.

In the modification shown in Figures 6 and 7, the numeral 50 indicates a rectangular wall casing having side walls 51 secured to an end closure 52 having a recess 53 which is divided with a horizontal rib 54. Slidably mounted in the casing 50 is a rectangular drawer 56 having a front wall 57 equipped with a pull 58 and side walls 59 and top and bottom walls 60 which are insulated as at 61. The rear ends of the side walls 59 are adapted to project into the upper part of the recess 53 and are slotted at their lower corners as at 63 to receive locking bolts 64.

The locking bolts 64 are in the form of inverted L-shaped extensions extending from rectangular plates 65 which have sliding movement in the recess 53 between its base and the rib 54, each of the plates 65 is provided with a horizontal slot 67 and each slot has a toothed rack 68 on one of its sides, both of which racks are engaged by the teeth of the lock mechanism pinion 29.

In operating the safe as shown in Figures 1 and 2, the cylindrical drawer 14 is inserted into the casing 1 and its arcuate lugs 19 are passed between and beyond the lugs 6. When the drawer has reached its ultimate inner position, it is turned about its horizontal axis to dispose its lugs 19 directly behind the lugs 6, the key 43 is turned in a clockwise direction, thus turning the pinion 29 which imparts an inward movement to the arcuate dog 11 to close up one of the spaces 7 between adjacent lugs 19, thus preventing the cylindrical drawer 14 from being turned about its horizontal axis. When the key reaches the locked position the discs 31, 32 and 33 are so placed that the ward strip 39 is bridged by the several peripheral gaps 37 and the springs 34 push the key outwardly and displace the discs longitudinally of the grooved shaft 27 so that said discs no longer register with the ward slots 40 and further rotation of the shaft 27 is prevented until the key is again thrust home, or to the inward limit of its movement. Obviously reversing the procedure will withdraw the arcuate dog 11, thus allowing the drawer to be rocked to register the lugs 19 with the spaces 7 and permit said drawer to be removed.

To open the drawer 56, the key is used to rotate the pinion and withdraw the bolts 64 from the slots 63 in opposite sides of said drawer.

What I claim as my invention is:

1. A wall safe comprising a casing adapted to be built into a wall, said casing having a rear end closure, a drawer adapted for insertion into the casing, a lock mechanism adapted to engage a drawer part within the casing, said lock mechanism including a lock barrel and a rocking shaft, an endwise movable member actuated by the rocking movement of said shaft to secure the drawer against removal from the casing, part of said lock mechanism being mounted to project beyond the casing and remote from the front of said casing, an elongated tube communicating between the lock mechanism and the front of the casing adapted to receive a key for operating the

lock mechanism, said tube being mounted on the outer periphery of the casing and extending longitudinally thereof.

2. A wall safe comprising a casing adapted to be built into a wall, said casing having an inner end closure, a drawer insertable into said casing, said drawer having a front to close the front opening and latching means adjacent its inner end, said end closure having latching means adapted to be engaged by the latching means of the drawer to prevent endwise movement of said drawer, means for locking the latching means, a tube positioned exteriorly of the casing, said tube supporting the locking means at one end and affording access thereto from a point adjacent the front opening.

3. A wall safe comprising a casing adapted to be built into a wall, said casing having an inner end closure, a drawer insertable into said casing, a set of circumferentially spaced lugs carried by the inner end closure and a set of coating circumferentially spaced lugs carried adjacent the inner end of the drawer, one set of said lugs being adapted for rocking movement to secure the drawer in its closed position, means for preventing relative rocking movement between the sets of lugs, a lock controlling said means, a tube positioned exteriorly of the casing supporting said lock at one end and affording access thereto from a point adjacent the front opening.

4. A wall safe comprising a casing adapted to be built into a wall, said casing having a rear end closure, a drawer adapted for insertion into the casing, a lock mechanism disposed adjacent the rear end closure, a tube positioned exteriorly of the casing connecting said lock mechanism and affording access thereto, and a movable member connected with the lock mechanism for securing the drawer against removal from the casing.
